DESIGN FOR LACE

Joseph D. Wiener, New York, N. Y.

Application July 13, 1934, Serial No. 52,575

Term of patent 3½ years

To all whom it may concern:

Be it known that I, JOSEPH D. WIENER, a citizen of the United States, residing at New York, in the county of New York and State of New York, have invented a new, original, and ornamental Design for a Lace, of which the following is a specification, reference being had to the accompanying drawing, forming part thereof.

The figure is a plan view of a lace, showing my new design.

The dot and dash lines shown in the drawing indicate a complete repeat unit of the design.

I claim:

The ornamental design for a lace, as shown and described.

JOSEPH D. WIENER
